CLAIM

The ornamental design for a fog light, as shown and described.

DESCRIPTION

FIG. 1 is an exploded perspective view of a fog light showing my new design;

FIG. 2 is a perspective view thereof, but shown without the lens for clarity of illustration;

FIG. 3 is a perspective view thereof, but shown with the lens;

FIG. 4 is a front elevational view thereof, but shown without the lens for clarity of illustration;

FIG. 5 is a front elevational view thereof, but shown with the lens;

FIG. 6 is a front elevational view thereof, but showing the lens separately for clarity of illustration;

FIG. 7 is a rear elevational view thereof showing the fog light;

FIG. 8 is a right side view thereof;

FIG. 9 is a left side view thereof;

FIG. 10 is a top plan view thereof; and,

FIG. 11 is a bottom plan view thereof.

The broken lines shown in the drawings illustrate environmental structure which forms no part of the claimed design.
